GAS BURNER

Martin Thorson, St. Charles, Ill.

Application January 23, 1933, Serial No. 652,995

5 Claims. (Cl. 158—119)

This invention relates to improvements in gas burners for household or commercial use. One object is to provide a gas burner that is capable of ready application to old or new heating plants without the necessity of altering the plant. A further object is to provide a gas burner having a very high degree of heating efficiency and one wherein a relatively great proportion of air is consumed with the gas, thus materially reducing the cost of burner operation.

A still further object is to provide a gas burner of simple construction and few parts, one that is compact in assembly, durable in use and not easy to get out of order and that is cheap to manufacture. A still further object is to provide a gas burner that can be regulated to provide a degree of heat in accordance with temperature changes, that is capable of manual or thermostatic control and one wherein a proper mixture of gas and air is always provided so that a silent, even combustion is assured, free from spluttering, recurrent ignition and the like, thus insuring the maintenance of a steady and continuous heat.

With the foregoing and other objects in view the invention consists in the combination and arrangement of parts to be hereinafter fully described, pointed out in the claims and illustrated in the accompanying drawing which forms a part of this application for patent and in which—

Fig. 1 is a top plan view of the burner partly in section to afford a better illustration.

Fig. 2 is a view of the burner partly in elevation and partly in section.

Fig. 3 is an enlarged detail sectional view of the burner.

Fig. 4 is a view of the perforated air collar before it is rolled or annularly formed.

Fig. 5 is a view of the burner illustrating its application to a heating plant.

Like reference characters denote corresponding parts throughout the several views.

The burner comprises essentially an outer air ring and an inner gas ring, the air ring being provided with a plurality of air tubes and the gas ring with a plurality of gas tubes disposed wholly within the air tubes, the air tubes being provided or formed with burner tips, a perforated air collar spacing the air and gas tubes apart adjacent the upper end of the gas tube.

The reference numeral 1 denotes a heating plant provided with the ash-pit door 2 and grate 3 and within the plant upon a suitable support 4 the gas burner is arranged, the central portion or ash dump portion of the grate having been removed. The gas burner includes an outer hol-

low ring 5 into which is tapped an air pipe 6, and an inner hollow ring 7 into which is tapped a gas pipe 8. The ring 7 is what may be termed a gas ring and it is of materially smaller diameter than the outer or air ring 5, so that a substantial space is provided between the rings. The rings are concentric.

Extending upwardly from the manifold ring assembly 5, 7 is a series of burner tube assemblies, each of which is generally indicated at 6. These burner tubes are preferably inclined with respect to the axis of the manifold rings 5, 7 so that the burner tubes are in a conical cluster or define in effect the frustum of a cone. These burner tubes comprise outer air tubes 9 which are tapped into the air ring 5. Within said air tubes and concentric therewith are the gas tubes 10 that are tapped into the gas ring 7, said gas tubes being of a diameter materially smaller than that of the air tubes so that a very considerable air space is formed between the tubes 9, 10. The outer ends of the gas tubes 10 are spaced inwardly from the corresponding ends of the air tubes and an elongated burner tip 11 having its outer end closed except for tiny perforations 12 is carried by each air tube.

Encompassing each gas tube 10 and spaced slightly from the free end thereof and completely filling the space between the gas tube and the surrounding air tube is the annular collar 13. Each collar 13 is provided with passageways 14 extending entirely through the collar and serving to conduct the air from the air tube 9 up into the mixing chamber defined within the upper end of the tube 9 and within the tube 11. These passageways 14 comprise upper portions, which all lie at an angle with respect to the axis of the collar and tube assembly. Hence, these passageways impart a whirling motion to the air as it enters the aforesaid mixing chamber comprising in part the interior of the tube 11. The whirling motion of the air is started just below the point of discharge of the gas from the gas tube 10, and this whirling motion is imparted to the discharging gas, resulting in an intimate commingling of the gas and the air. The relatively long length of the cylindrical mixing chamber defined within the tube 11 is advantageous for insuring thorough mixing of the gas and air prior to the ignition of the mixture. This ignition only takes place outside of or beyond the relatively restricted orifice or orifices 12 in the upper end of the tube 11.

The burner is so placed within the heating plant that its tubes 9 and tips 11 extend up

through the grate 3 when the ash dump portion thereof is removed. The upper surface of the grate 3 is preferably covered with insulation 15 held in place by angle pieces 16. Referring again to the air pipe 6, the same extends out through the door 2 of the heating plant and is provided with a control valve 17 and leads to a motor operated blower 18 disposed outside the heating plant. The gas pipe 8 likewise extends through the door 2 and is provided with the valve 19 and leads to the supply pipe or main. The valves 17, 19 are provided with handles connected to the control rod 20 that is operatively supported in the base 21 arranged upon the floor and that extends upwardly through the basement ceiling into a room of the building for manual operation. By manually raising the slide rod 20 the valves 17, 19 may be opened and by depressing said rod the valves may be partly or wholly closed. A finger 22 carried by the rod 20 works over the indicator 23 secured to the heating plant wall and graduated in a manner to denote by the position of said finger whether the valves 17, 19 are open, partly open, or closed. A pilot pipe 24 provided with a valve 25 extends through the wall of the heating plant into close proximity to the burner tips to ignite the gas mixture released therefrom.

The sliding control rod 20 may, of course, be operated by a thermostat if desired. When the gas and air are turned on the blower motor is started and the gas and air enter the rings 7, 5 respectively, the gas passing through the burner tubes 10 and out into that portion of the tubes 9 beyond the collars 13 and then into the gas burner tips 11. The air from the ring 5 passes out through the tubes 9 and through the several air passages 14 in the collar 13 to mix with the gas. The angular formation of the air passages 14 directs the air, under pressure, into the gas from the gas tubes and a fuel turbulence chamber is formed in that part of the air tube beyond the collar and in the gas tip and the thoroughly mixed fuel coming out through the perforation 12 is ignited by the gas pilot, the flame being directed against any suitable baffle plate (not shown) that may be disposed upon the grate inside the circle of gas tips, such plate or plates being preferably made of a good heat conducting material. The fuel within the turbulence chamber is preheated in a very efficient manner after the burner is in operation for a short period of time.

While the foregoing is one embodiment of my invention it is to be understood that changes and modifications may be resorted to without departure from the scope or spirit of the invention as defined in the claims.

What is claimed is:—

1. In a gas burner, the combination of an outer hollow manifold ring, an inner hollow manifold ring within said outer ring, means for supplying air under pressure to said outer manifold ring, means for supplying gas under pressure to said inner manifold ring, a series of burner tubes disposed at spaced points around said manifold rings and extending upwardly therefrom and inclined at an angle to the vertical axis of said rings whereby said burner tubes define in effect the frustum of a cone, each of said burner tubes comprising an outer air tube secured to and communicating with said outer manifold ring, an inner gas tube within said outer air tube and secured to and communicating with said inner manifold ring, an annular member interposed between said inner

and outer tubes adjacent to the upper end of said inner tube, passageways in said annular member inclined across the axis of said annular member for imparting a whirling motion to the air passing upwardly through said passageways, a relatively long cylindrical tube extending beyond said annular member and defining a relatively long mixing chamber above said inclined passageways, said inclined passageways discharging air from said outer air tube into said mixing chamber with a whirling motion, and said inner gas tube discharging gas into said mixing chamber within said whirling volume of air, and an orifice in the upper end of said cylindrical tube of smaller diameter than the interior of said tube.

2. In a gas burner, the combination of an outer hollow manifold ring, an inner hollow manifold ring within said outer ring, means for supplying air under pressure to said outer manifold ring, means for supplying gas under pressure to said inner manifold ring, a series of burner tubes disposed at spaced points around said manifold rings and extending upwardly therefrom and inclined at an angle to the vertical axis of said rings whereby said series of burner tubes define in effect the frustum of a cone, each of said burner tubes comprising an outer air tube secured to and communicating with said outer manifold ring, an inner gas tube within said outer air tube and secured to and communicating with said inner manifold ring, a relatively long mixing chamber extending beyond the upper end of each inner gas tube, the air from said outer air tube and the gas from said inner gas tube contacting adjacent to the lower end of said mixing chamber and passing upwardly through said mixing chamber, and an orifice in the upper end of said mixing chamber of smaller diameter than the interior of said mixing chamber.

3. In a gas burner adapted for installation in a heating plant of the type having a grate provided with a substantially circular central opening and an ash-pit below the grate, the combination of an outer hollow manifold ring, an inner hollow manifold ring within said outer ring, said manifold rings being adapted for disposal within said ash-pit below the grate, means for supplying air under pressure to said outer manifold ring, means for supplying gas under pressure to said inner manifold ring, a series of burner tubes disposed at spaced points around said manifold rings, said burner tubes extending upwardly and inwardly in a conically shaped cluster for extending upwardly and inwardly through the substantially circular central opening within the grate, each of said burner tubes comprising an outer air tube secured to and communicating with said outer manifold ring, an inner gas tube within said outer air tube and secured to and communicating with said inner manifold ring, and means associated with the upper portion of each burner tube for causing commingling of the air and gas prior to ignition.

4. In a gas burner adapted for installation in a heating plant comprising a furnace having a removable grate member and an ash-pit therebelow, a hollow air manifold defining in plan an open and unobstructed frame for positioning within the ash-pit in substantially concentric relation to the furnace, a hollow gas manifold disposed within the air manifold in concentric spaced relation thereto, burner tube assemblies extending upward from said manifolds, said assemblies being disposed and of proper length to extend upward through and beyond the opening provided by removal of said grate member, the burner tube

assemblies each comprising an outer air tube opening at its lower end into the air manifold and an inner gas tube opening at its lower end into the gas manifold, and means for supplying gas and air to the respective manifolds.

5. In a gas burner adapted for installation in a heating plane comprising a furnace having a removable grate member and an ash-pit therebelow, a hollow air manifold defining in plan an open and unobstructed frame for positioning within the ash-pit in substantially concentric relation to the furnace, a hollow gas manifold disposed within the air manifold in concentric spaced

relation thereto, burner tube assemblies extending upward from said manifolds, said assemblies being disposed and of proper length to extend upward through and beyond the opening provided by removal of said grate member, the burner tube assemblies each comprising an outer air tube opening at its lower end into the air manifold and an inner gas tube opening at its lower end into the gas manifold, and means for supplying gas and air to the respective manifolds, the space enclosed by the air manifold being open and unobstructed from beneath said air manifold.
